UNITED STATES PATENT OFFICE.

SIDNEY A. KELLER, OF NEW YORK, N. Y.

DESIGN FOR A HANDLE FOR BUTTON-HOOKS, &c.

SPECIFICATION forming part of Design No. 31,546, dated September 26, 1899.

Application filed July 27, 1899. Serial No. 725,323. Term of patent 3 $\frac{1}{2}$ years.

To all whom it may concern:

Be it known that I, SIDNEY A. KELLER, a citizen of the United States, and a resident of New York, in the county of New York and State of New York, have invented a certain new and useful Design for Handles for Button-Hooks and Similar Articles, of which the following is a specification, wherein reference is made to the accompanying drawing and the letters thereon, which form a part of this application and which show the article in elevation and together furnish a clear and exact description of my design, which is essentially as follows:

5 The leading feature of my design is a handle for button-hooks and similar articles ornamented with scrolls in the upper half, inclosing two shields and capped at the top and the sides by small knobs. The lower half is a hexagonal body beaded at the intersections of the sides.

More particularly described, it consists of groups of scrollwork marked B L E M I J K, which all inclose by their symmetrical combinations several shields, particularly calling attention to those marked C and D. The contour of the upper half rather suggests an

elongated shield tipped at the points marked $\alpha \alpha \alpha$ by small knobs. The lower half is a long hexagon, the drawing showing the side F in full view, with the adjoining sides N and O separated by continuous borders of beading G G. Each of the sides is slightly concaved to give the beading more prominence.

Below the hexagon the design is completed by some more scrollwork inclosed in a sphere I, resting upon two sections of a sphere P.

The design is finally completed by some more scrollwork flanked by small circlets R in a bell-shaped base.

Having thus described my invention, what I claim as new, and desire to secure by Letters Patent, is—

The design for a handle for button-hooks and similar articles substantially as herein shown and described.

Signed at New York, in the county of New York and State of New York, this 21st day of July, 1899.

SIDNEY A. KELLER.
